PROCESS FOR THE SELECTIVE CRACKING
OF HYDROCARBONSJoseph F. Donnelly, Lemont, Ill., assignor to
Donnelly Process Corporation, Chicago, Ill., a
corporation of Nevada

Application March 15, 1935, Serial No. 11,211

13 Claims. (Cl. 196—60)

My invention relates to a method for the selective cracking of hydrocarbons and particularly to a method for the cracking treatment of petroleum hydrocarbons wherein the production of detrimental carbon is avoided and the degree of cracking practiced is further governed by the molecular structure of the more complex fractions of the stock to be converted.

A general object of my invention is to provide for the pyrolytic treatment of hydrocarbon fluids wherein the more complex fractions thereof undergo a molecular rearrangement productive of compounds of improved characteristics.

Another object of my invention is to provide, under such pyrolytic treatment as immediately above described, for the production of crackable fractions of constant characteristics, and to subject selective fractions thereof to coil cracking conditions of temperature, time and pressure, cooperatively formative of lighter and heavier fractions respectively adapted to subsequent vapor phase and liquid or liquid-vapor phase cracking.

A further object of the invention is to provide for the separate and simultaneous pyrolytic cracking treatment of selective fractions under different cracking conditions best suited to produce a maximum gasoline yield of desirable octane rating unaccompanied by the formation of detrimental carbon.

A specific purpose of the invention is to provide a cracking process for the molecular alteration of relatively heavy hydrocarbons, such as crude oil or topped crude, into gasoline and other light hydrocarbons and into low viscosity residual oil, wherein a distillate fraction such as gas oil or lubricating distillate intermediately derived by a known method of distillation from such relatively heavy hydrocarbons, is submitted to moderate cracking conditions (illustratively 825° to 925° F.) in a primary zone for a period formative of substantial quantities of fractions boiling under and above approximately 625° F. respectively, the thus obtained fractions released to and separated in a second zone, released from said second zone and the fraction boiling under approximately 625° F. subjected in a third zone to vapor phase cracking under conditions formative of gasoline of high anti-knock rating, the products of such vapor phase treatment while still undergoing active cracking commingled in a fourth zone with a portion of the fraction boiling above approximately 625° F. separated in said second zone and/or with the relatively heavy charge oil (topped crude, etc.) at a temperature

permitting further cracking of the latter in such zone; wherein the treatment is continued in said fourth zone for a period formative of an additional quantity of fractions lighter than the charge oil accompanied by a substantial viscosity reduction thereof, but under conditions inhibitive of detrimental free carbon formation and wherein the products from said fourth zone are released to a separator from which low viscosity fuel oil is withdrawn from the system, the corresponding vaporous fraction conducted to a dephlegmator from which reflux condensate (distillate or gas oil) is returned to said first zone for treatment in the manner aforesaid and high anti-knock gasoline is released for condensation according to standard practice.

In carrying out the invention, I preferably initially subject the raw stock to be converted (crude oil, reduced crude, etc.) to a moderately high temperature and pressure, but under so short a time factor that the initial conversion is of a relatively mild order; the reaction being more of a molecular rearrangement of the heavier constituents, as evidenced by reduction in viscosity of the heavier fraction.

The portion of heavy distillate such as raw and/or recycle gas oil obtained through partial vaporization of the raw stock treated as above described, and/or obtained from the cracked products, is primarily subjected to so-called liquid, or liquid-vapor phase cracking, preferably in a coil of conventional type where a moderately high temperature and pressure (illustratively 825° to 925° F. and 100 to 1000 lbs., respectively) is imposed under a time factor formative of low octane rating gasoline and other relatively light fractions, but inhibitive of substantial asphaltic degradation and wherein such time and temperature treatment is further regulated to effect a limited molecular change of the oil undergoing treatment permitting additional subsequent cracking thereof productive of a further quantity of gasoline and other relatively light fractions. Summarizing; such primary treatment causes a rearrangement of the molecular structure resulting in the formation of a wider boiling range product which is subsequently separated into two major fractions, one as liquid boiling above approximately 625° F., the other as vapor boiling under approximately 625° F. and containing gasoline of relatively low octane rating and other relatively light fractions.

By separating the products of such primary cracking treatment into vaporous and liquid portions before detrimental asphaltenes obtain, sub-

55

- jecting the vaporous portion to an increased temperature for a period formative of additional gasoline of desired higher octane rating, then admixing in a separate zone a portion of the 5 vapor cracked products while at a high cracking rate temperature (illustratively 925° to 1125° F.) with a portion of the separated liquid product and/or heavy charge oil supplied from an extraneous source, also at a cracking temperature 10 (illustratively 775° to 900° F.) and carefully regulating the duration of treatment in said zone as to inhibit detrimental free carbon separation but permit of the production of an additional amount of gasoline and other relatively light 15 fractions while maintaining therein a pressure preventive of complete vaporization of fractions otherwise vaporizable at the obtaining temperature, a gasoline of 65 or higher octane rating is obtained.
- 20 Although according to the invention primary subjection of heavy hydrocarbons to the pyrolytic treatment before described is necessary to produce a cracking stock therefrom that will withstand vapor phase cracking temperatures (illustratively 925° to 1125° F.) in order to yield a high percentage of gasoline of superior octane rating, i. e., 65 or above, the supply of such cracking stock may be augmented through the introduction 25 of corresponding fractions derived from extraneously supplied gasoline, naphtha or kerosene of low octane value which require pyrolytic treatment to effect the desired degree of molecular change.
- 30 An additional quantity of gasoline is produced 35 by admixing the products from the vapor phase cracking coil, while still in an active state of cracking, with preheated heavy fractions such as lubricating oil distillate, topped crude oil, etc., followed by maintaining such admixture at an active cracking temperature in a separate zone (well-insulated to avoid heat loss) under a pressure preventive of complete vaporization of the 40 vaporizable fractions obtaining in said zone. If required, the maintenance of an active cracking 45 temperature of the mixture may be aided by applying heat to the last mentioned zone.
- The present invention employs at least two, and may employ three, of the well-known and 50 understood pyrogenic phases of cracking; that is vapor phase, liquid-vapor phase, and liquid phase, working co-operatively and simultaneously in a new manner as to produce better economic results than have heretofore been obtainable.
- 55 The oil undergoing treatment in coils 27 and 27' enters in liquid phase and may or may not progress into liquid-vapor phase depending on the depth of cracking and the pressure obtaining therein.
- 60 The oil undergoing treatment in coils 33 and 33' enters in vapor phase, or it may enter in liquid phase and be substantially completely vaporized before, or simultaneously with cracking therein.
- 65 The present invention provides a plurality of 65 simultaneously operative, selective, differential heat treatments whereby a preferred fraction is treated in one zone to cracking conditions formative of fractions best suited to vapor phase, and 70 to liquid or liquid-vapor phase cracking, respectively, whereby such converted fraction is separated into vaporous and liquid fractions in a separate zone, whereby the vaporous fraction is treated to cracking conditions formative of high anti-knock gasoline in another separate zone;

and whereby the vapor cracked products while still at high cracking rate temperature, and the separated liquid fraction and/or heavy charge oil (preferably also at a cracking temperature) are commingled in still another separate zone 5 wherein the vapor phase cracking is decelerated, the liquid phase cracking rate accelerated, and the cracking continued to the desired degree.

In order that the invention may be better understood, reference is made to the accompanying 10 diagrammatic drawings; Fig. 1 representing one form of apparatus suitable for carrying out the process, and Fig. 2 a simplified flow diagram having the same reference numbers as the corresponding instrumentalities of Fig. 1. 15

Referring to the drawings: in the normal or preferred operation of the process the charging pump 1 delivers the raw stock to be treated (such as crude oil, reduced crude or heavy distillate) from any convenient source of supply (not 20 shown) through the line 2, and heat exchanger 3, thence through lines 4 and 52 to contact hot cracked products issuing from coils 5 and/or 33'. However the charge oil may be heated to the desired temperature in any convenient manner, 25 the place of introduction of the oil into the system being determined in accordance with its characteristics and the degree of refinement desired or required; i. e., oil to be distilled only may be introduced through line 4 and 18 as controlled by valve 18', to contact hot fluid flowing through line 7'. Oil to be treated to viscosity cracking, i. e., the preferred method of operation, is introduced through line 52, as controlled by valve 53 in the manner aforesaid. 30

When the recycle oil from the fractionating tower 20 is introduced by pump 22 to coil 5 alone, or in admixture with recycle oil withdrawn from separator 29, i. e., the preferred method; or optionally when the recycle oil separated in 29 is 40 alone introduced into coil 5, the oil is heated therein to an active cracking temperature and discharging through line 34, as controlled by valve 34', is directly admixed with the charge oil issuing from line 52 and in the normal operation further admixed with a portion of the cracked products effluent of coil 33'. This mixture is then treated in coil 51 to cracking conditions formative of desirable recycle oil, gasoline and low viscosity residual fractions. 50

Zone 51 is preferably a series of continuous connected pipes dimensioned and designed to assure an intimate physical contact of vaporous and liquid products during the treatment therein. Such coil arrangement may be also replaced by a chamber dimensioned and arranged to operate in the same manner. 55

When the fresh charge oil introduced by pump 1 is of a composition liable to precipitate deleterious carbon upon cracking to the extent of substantial gasoline production but requires a decided viscosity reduction, it is preferably pre-heated to a degree that when admixed with the products effluent of coils 5 and 33' the temperature in the coil 51 will be sufficient to effect the desired viscosity cracking under regulated conditions preventive of detrimental carbon formation therein. 60

In its passage through coil 5 the oil is heated 70 to an extent that it will rapidly raise the charge oil to the desired cracking temperature when admixed therewith, or to an extent that when additional heat is supplied thereto by the cracked products effluent of coil 33' a temperature will be 75

immediately attained productive of further cracking thereof in coil 51. The treatment in coil 51 is conducted without detrimental carbon formation and is of an order that upon releasing the thus treated mixed stock, as controlled by valve 51'', to the chamber 9 and permitting partial vaporization to occur, the resultant residuum withdrawn through line 10 and cooler 11, as controlled by valve 10, is of superior commercial characteristics, particularly as to an improved viscosity over a residuum produced from the same charge oil under non-cracking or ordinary distillation conditions.

When treating certain types of highly viscous oil (such as asphaltic crude oil or its residues) to reduce its viscosity without detrimental carbon deposition, I have found it very advantageous to mix such oil preferably preheated to an incipient cracking temperature with a predominant portion of oil that is relatively refractory compared to said viscous oil (illustratively recycle gas oil), said refractory oil having been previously heated to a temperature (illustratively 800° to 900° F.) sufficient to substantially immediately raise the temperature of the viscous oil to an accelerated cracking temperature (illustratively 800° to 900° F.) when admixed therewith, but without material cracking of the refractory oil occurring during heating; continuing the treatment of the mixture under sufficient pressure to prevent excessive vaporization of the refractory oil until the desired amount of viscosity cracking is attained, and then separating the mixture by vaporization. It will be noted that the above method of viscosity cracking is the previously mentioned preferred method of operation with emphasis directed to maintaining a predominant mass of refractory solvent menstruum (recycle oil) in which the oil to be treated is cracked; the detailed operation when viscosity cracking as above described being as follows: the oil to be treated to said cracking is delivered by pump 1 through line 2, heat exchanger 3, line 52 and valve 53, where optionally admixed with a portion of oil from the bottom of separator 29 as delivered through line 30 and valve 30'', it is then commingled with one to twenty times its volume of recycle condensate issuing from coil 5 through line 34, said condensate being withdrawn from the base of fractionator 20 and delivered by pump 22 through line 23 and valve 26'' to said coil, wherein it is heated in liquid or liquid-vapor phase to an extent that without itself undergoing material cracking it will heat the above oil or mixture sufficiently to effect the desired cracking, the thus heated recycle oil passing through pressure control valve 34' and is admixed as above stated. This mixture is then passed through valve 51' into coil 51 wherein it is maintained for sufficient duration to effect the desired further cracking but preventive of detrimental carbon formation, and under a pressure as controlled by valve 51'' inhibitive of excessive vaporization of asphaltene solvents. When viscosity cracking as above described, I prefer to admix the products effluent of coil 33' with the effluent of coil 51 by passing said products through line 7 as controlled by valves 8 thus departing from the normal method of precommingling of said products effluent with the effluent of coil 5 before passage through said coil 51; and 8', although if the partial pressure effect of the light product content of said effluent 75 does not cause excessive vaporization in coil 51,

a portion of coil 33' effluent may be admixed (normal method) with the material entering coil 51. I may also admix a portion of liquid delivered from separator 29 through line 30 as controlled by valve 30'' with the effluent of coils 33' 5 and 51. In any case the thus treated products pass through line 7' into separator 9 where exists a pressure lower than previous and the residual products are separated as liquid from lighter products as vapor. It is to be understood that the treatment in coils 21, 27', 33 and 33' is always substantially the same regardless of the operative conditions employed in coil 51.

The vapor separating in the vaporizer 9 escapes through dome 12, to enter the partial condenser 13, whence heavy reflux condensed therein is withdrawn through line 14, as governed by valve 15, and charged through the agency of pump 16 discharging through line 17, via line 4 normally to heating coil 5 and/or optionally via lines 4 and 52 to coil 51.

While the partial condensation of the vapors separated in 9 is not essential to the process, it is preferable to condense out the very heavy fractions of said vapor (accomplished in any well-known manner) and treat such condensate to relatively mild cracking formative of fractions suitable to subsequent severer cracking conditions. This is accomplished in the present process by returning said condensate as above described and treating it to the cracking conditions established in coils 5 and/or 51. Further, I have found by the condensation and removal of such heavy fractions that the heavy condensate produced, separated and accumulated in the bottom of fractionator 20, is of more desirable character for cracking under the herein prescribed treatment in coils 21 and 27'.

The vapors separated in the partial condenser 13 and containing gasoline fractions produced 40 under selective cracking treatments herein described, escape through line 19 to enter the shell of exchanger 3, next discharging to bubble fractionating tower 20, whence condensed heavy recycle oil is withdrawn through line 21, as governed by valve 21'. The withdrawn oil is pumped by the high pressure pump 22 through line 23, any desired portion thereof not required for comminglement with the raw stock undergoing viscosity cracking being directed to coil 27 50 through heat exchanger 24, or passed directly to coil 27 by proper manipulation of valves 23', 25' and 26', thence through line 26 to enter said coil disposed in the left-hand convectional pass of furnace 6. The products from coil 27 enter the 55 radiant coil 27' and flow therefrom via line 28 through the heat exchanger 24, as controlled by valve 28', to finally discharge into the high pressure vapor separator 29. It will also be noted that line 26, equipped with valve 26'', forms a 60 connection with lines 23 and 30, through which the portion of heavy recycle oil employed as a cracking agent in the preferred method of operation is introduced into heating coil 5. It will also be noted that line 31, equipped with valve 65 31', forms a connection with line 32 through which a portion of the heavy recycle oil may be passed through line 32 and coil 33. Normally valve 31' is closed.

Vaporous fractions separating in the high 70 pressure vapor separator 29 pass off through vapor line 35, as controlled by valve 35' (normally valve 32' being open and valve 35'' being closed), thence through line 32, to coil 33 and 33' for vapor phase cracking treatment. If desired the 75

vapor from 29 may be condensed in a well-known manner and the condensate delivered to coil 33 under the pressure of the separator 29 or by a pump.

5 Line 35 controlled by valve 35'' extends to fractionator 20 for emergency use such as starting and stopping of operations; line 31 controlled by valve 31' is used likewise, all of which valves being normally closed; line 7 controlled by valves 8 and 8' is used as a by-pass for coil 51. It is to be noted that the flow of gases through the zones containing the heating coils 5, 27 and 33 is controlled by regulation of dampers in the outlet of said zones and the waste gases are led to 15 a stack (not shown).

The liquids separated in the high pressure vapor separator 29, may be released under its own pressure through lines 36, 37 and 30, as controlled by valves 30', 30'', 30''' and 38 and passed to the 20 inlet of coil 5, or 51, or to the outlet of coil 51; or such liquid may flow to pump 41 and the pump pressure be imposed on line 30 during such distribution.

A portion of crude gasoline, naphtha or kerosene of relatively low octane rating, from any suitable source of supply 42, may be employed to supplement the fractions subjected to vapor phase treatment, and to such end may be conveniently introduced as trim stock to the high 30 pressure vapor separator 29 through line 43, controlled by valve 43', to the suction of pump 44 and thence by lines 45 and 46, as controlled by valves 45' and 46', to the top of the separator; or such stock may be admitted via lines 45 and 47, as 35 controlled by valves 45', 46' and 47' to the upper shell of heat exchanger 24, and thence via line 48, controlled by valve 48' to the mid-section of the separator 29, or such stock may be delivered as liquid to coil 33 by making suitable valve adjustments subsequently described.

40 A portion of the stock from tank 42 may be admitted through lines 45 and 49, as controlled by valves 45', 45'' and 49', to the coil of the partial condenser 13, thus serving to condense very heavy fractions of the vapor leaving the chamber 9 while becoming itself preheated to a material degree.

It is preferable that the light stock to be subjected to vapor phase cracking in coils 33 and 33' be substantially completely vaporized before 50 entering said coils although it is within the scope of the invention to vaporize and crack such stock in the coils 33 and 33'.

Further, a portion of the light stock supplied 55 from extraneous source 42 or from accumulator 57, or mixtures thereof, may be passed in indirect heat exchange with the products effluent of coil 51 in a well-known manner (not shown) to regulate the temperature thereof and to preheat the 60 light stock.

The light stock discharged through the coil of the partial condenser 13 is forced under the obtaining pump pressure through line 50 to the vapor phase cracking coil 33 and 33', disposed 65 in the right-hand convective pass of furnace 6. The cracked products from coils 33 and 33' pass through line 40, as controlled by valve 40' and enter the tube bank 51 while still undergoing active cracking (normal method), or are passed 70 through line 7 as controlled by valves 8 and 8' to be admixed with the effluent of coil 51 (practice employed in treating highly viscous oil). It will be observed that the products of coil 5 as controlled by valve 34' may be commingled with 75 quantities of charge oil from line 52 as controlled

by valve 53 (preferred operation), and/or with quantities of liquid from the bottom of separator 29 as controlled by valve 30''' (optional) and with quantities of the products effluent of coil 33' as controlled by valve 40' and the mixture passed 5 through coil 51 as controlled by valves 51' and 51'' (preferred operation); or the products of coil 5 may be admixed with charge oil only and this mixture passed through coil 51, while the products effluent of coil 33' and the liquid from the bottom 10 of separator 29 are admixed with the effluent of coil 51 (practice employed in treating highly viscous oil); these various operations being accomplished by proper setting of valves provided for the purpose, and commonly understood by those 15 skilled in the art to which the invention relates. Heavy condensate from the partial condenser 13, as delivered by pump 16 may likewise be delivered in selective quantities through lines 4 and/or 52 as controlled by valves 4', 4'' and 53 to be ad- 20 mixed with the products entering coil 5 or 51.

Light recycle oil may be selectively withdrawn from the bubble tower 20 by lines 54, 55 and 56, as respectively controlled by valves 54', 55' and 56' and accumulated in tank 57, whence portions thereof may be pumped by pump 58 via lines 45, 46, 47, 48 and 49 to the coil of the partial condenser 13, or to separator 29 by a proper setting of valves 45', 45'', 45''', 46', 47', 48', 49', 25 23' and 25', and thereafter to the vapor phase 30 cracking coil 33 and 33' for recracking treatment therein. Light vapors separating in the accumulator 57 are returned to the bubble tower 20 by line 59 as controlled by valve 59'.

It is a feature of the process to so regulate 35 the flow through the various cracking zones that the selective fractions concurrently subjected to their respective heat treatments will be cracked to the desired degree without formation of detrimental carbon, not only during the active crack- 40 ing periods, but in any subsequent treatment of the cracked products. To this latter end it is essential to entirely stop or decelerate the crack- 45 ing rate of the complex fractions contained in the effluent of the zone 51, this being accom- 50 plished in any one of the following ways, or combi- 55 nations thereof; such as normally cooling the products effluent of the final reaction zone before or after pressure release by direct admixture with a cooling medium, preferably cooler oil; or by indirect heat exchange with a cooler fluid sub- 60 stance; or by regulation of duration of separated residual oil in separator 9 by withdrawing the separated residual products therefrom substan- 65 tially immediately on separation.

Gasoline vapors fractionated in the bubble tower 20 pass off through vapor line 60 to condenser 61. The condensate therefrom flows through line 62 to accumulate in receiver 63 from whence liquid gasoline is withdrawn from the 60 system through line 64, as controlled by valve 64'. Fixed gas escapes through line 65, as controlled by valve 65', which is preferably of automatic operation. Any gasoline necessary for trim control may be withdrawn from receiver 63 65 by line 66, and pumped by pump 67 through line 68 to trim spray coil 69.

It is to be further understood that the apparatus is equipped with suitable indicating and recording devices for observation and registration of pressures, temperatures, flow, etc., and that the apparatus is insulated where it is desirable to maintain or regulate heat. Further, the invention is not limited to the particular form of apparatus herein described, nor to the specific 75

temperatures and pressures mentioned, which are given by way of example only.

What I claim as new and desire to protect by Letters Patent is:

- 5 1. Process for producing anti-knock gasoline and low viscosity fuel oil which comprises commingling heavy hydrocarbon such as crude petroleum or reduced crude with hotter, fluid hydrocarbon, imposing through such comminglement cracking conditions of heat and pressure on said heavy hydrocarbon, reducing the viscosity thereof by continuing said cracking conditions, separating generated vapors from residuum and withdrawing the latter as low viscosity fuel oil, dephlegmating the vapors to condense and separate reflux condensate from gasoline vapors and separately condensing the latter as anti-knock gasoline, subjecting the reflux condensate to cracking conditions of heat and pressure, separating generated vaporous fractions from residual fractions and separately subjecting such fractions to vapor and liquid phase cracking respectively, commingling products of such cracking treatments as said hotter, fluid hydrocarbon with said heavy hydrocarbon and continuing the process in the manner aforesaid.
- 10 2. Process for producing anti-knock gasoline and low viscosity fuel oil which comprises commingling heavy hydrocarbon such as crude petroleum or reduced crude heated to a cracking temperature with hotter, fluid hydrocarbon and accelerating thereby the cracking rate of said heavy hydrocarbon, reducing the viscosity of said heavy hydrocarbon by continuing such accelerated cracking rate, separating generated vapors from residuum and withdrawing the latter as low viscosity fuel oil, dephlegmating the vapors to condense and separate reflux condensate from gasoline vapors and separately condensing the latter as anti-knock gasoline, subjecting the reflux condensate to cracking conditions of heat and pressure, separating generated vaporous fractions from residual fractions and separately subjecting such fractions to liquid and vapor phase cracking respectively, commingling products of such cracking treatments as said hotter, fluid hydrocarbon with said heavy hydrocarbon and continuing the process in the manner aforesaid.
- 15 3. Process for producing anti-knock gasoline and low viscosity fuel oil which comprises commingling a stream of heavy hydrocarbon such as crude petroleum or reduced crude heated to a cracking temperature with a stream of hotter, fluid hydrocarbon, accelerating thereby the cracking rate of said heavy hydrocarbon and reducing the viscosity thereof by continuing such accelerated cracking rate for an interval short of detrimental carbon separation, separating generated vapors from residuum and withdrawing the latter as low viscosity fuel oil, dephlegmating the vapors to condense and separate reflux condensate from gasoline vapors and separately condensing the latter as anti-knock gasoline, subjecting the reflux condensate to liquid phase cracking conditions of heat and pressure for an interval short of substantial asphaltic degradation, separating generated vaporous fractions from residual fractions before detrimental asphaltenes obtain, subjecting the vaporous fractions to vapor phase cracking for an interval short of detrimental carbon formation, uniting the products of such vapor phase cracking at their cracking temperature with residual fractions as said hotter, fluid hydrocarbon, commingling the latter with said heavy hydrocarbon and continuing the process in the manner aforesaid.
- 20 4. Process for producing anti-knock gasoline and low viscosity fuel oil which comprises commingling a stream of heavy hydrocarbon such as crude petroleum or reduced crude heated to 775-900° F. with a stream of hotter, fluid hydrocarbon, accelerating thereby the cracking rate of said heavy hydrocarbon, reducing the viscosity and increasing the light fraction content thereof by prolonging such accelerated cracking rate under a pressure preventive of complete vaporization and for an interval short of detrimental carbon formation, separating generated vapors from residuum and withdrawing the latter as low viscosity fuel oil, dephlegmating the vapors to condense and separate reflux condensate from gasoline vapors and separately condensing the latter as anti-knock gasoline, subjecting the reflux condensate to 25 825-925° F. under 100-1000 lbs. pressure for an interval short of detrimental carbon formation, separating generated vaporous fractions from residual fractions as products boiling under and above approximately 625° F. respectively, subjecting the vaporous fractions to vapor phase cracking at 925-1125° F. for an interval short of detrimental carbon formation, uniting the products of such vapor phase treatment with the residual 30 fractions substantially at their respective cracking temperatures as said hotter, fluid hydrocarbon, commingling the latter with said heavy hydrocarbon and continuing the process in the manner aforesaid.
- 25 5. Process for producing anti-knock gasoline and low viscosity fuel oil which comprises commingling a stream of heavy hydrocarbon such as crude petroleum or reduced crude heated to 775-900° F. with a stream of hotter, fluid hydrocarbon, accelerating thereby the cracking rate of said heavy hydrocarbon, reducing the viscosity and increasing the light fraction content thereof by prolonging such accelerated cracking rate under a pressure preventive of complete vaporization and for an interval short of detrimental carbon formation, separating generated vapors from residuum and withdrawing the latter as low viscosity fuel oil, dephlegmating the vapors to condense and separate reflux condensate from gasoline vapors and separately condensing the latter as anti-knock gasoline, subjecting the reflux condensate to 35 925-1125° F. for an interval short of detrimental carbon formation, uniting the products of such vapor phase treatment with the residual fractions substantially at their respective cracking temperatures as said hotter, fluid hydrocarbon, commingling the latter with said heavy hydrocarbon and continuing the process in the manner aforesaid.
- 40 6. Process for producing anti-knock gasoline and low viscosity fuel oil which comprises commingling a stream of heavy hydrocarbon such as crude petroleum or reduced crude heated to 775-900° F. with a stream of hotter, fluid hydrocarbon, accelerating thereby the cracking rate of said heavy hydrocarbon, reducing the viscosity and increasing the light fraction content thereof by prolonging such accelerated cracking rate under a pressure preventive of complete vaporization and for an interval short of detrimental carbon formation, separating generated vapors from residuum and withdrawing the latter as low viscosity fuel oil, dephlegmating the vapors to condense and separate reflux condensate from gasoline vapors and separately condensing the latter as anti-knock gasoline, subjecting the reflux condensate to 45 925-1125° F. for an interval short of detrimental carbon formation, uniting the products of such vapor phase treatment with the residual fractions substantially at their respective cracking temperatures as said hotter, fluid hydrocarbon, commingling the latter with said heavy hydrocarbon and continuing the process in the manner aforesaid.
- 50 7. Process for producing anti-knock gasoline and low viscosity fuel oil which comprises commingling a stream of heavy hydrocarbon such as crude petroleum or reduced crude heated to 775-900° F. with a stream of hotter, fluid hydrocarbon, accelerating thereby the cracking rate of said heavy hydrocarbon, reducing the viscosity and increasing the light fraction content thereof by prolonging such accelerated cracking rate under a pressure preventive of complete vaporization and for an interval short of detrimental carbon formation, separating generated vapors from residuum and withdrawing the latter as low viscosity fuel oil, dephlegmating the vapors to condense and separate reflux condensate from gasoline vapors and separately condensing the latter as anti-knock gasoline, subjecting the reflux condensate to 55 925-1125° F. for an interval short of detrimental carbon formation, uniting the products of such vapor phase treatment with the residual fractions substantially at their respective cracking temperatures as said hotter, fluid hydrocarbon, commingling the latter with said heavy hydrocarbon and continuing the process in the manner aforesaid.
- 60 8. Process for producing anti-knock gasoline and low viscosity fuel oil which comprises commingling a stream of heavy hydrocarbon such as crude petroleum or reduced crude heated to 775-900° F. with a stream of hotter, fluid hydrocarbon, accelerating thereby the cracking rate of said heavy hydrocarbon, reducing the viscosity and increasing the light fraction content thereof by prolonging such accelerated cracking rate under a pressure preventive of complete vaporization and for an interval short of detrimental carbon formation, separating generated vapors from residuum and withdrawing the latter as low viscosity fuel oil, dephlegmating the vapors to condense and separate reflux condensate from gasoline vapors and separately condensing the latter as anti-knock gasoline, subjecting the reflux condensate to 65 925-1125° F. for an interval short of detrimental carbon formation, uniting the products of such vapor phase treatment with the residual fractions substantially at their respective cracking temperatures as said hotter, fluid hydrocarbon, commingling the latter with said heavy hydrocarbon and continuing the process in the manner aforesaid.
- 70 9. Process for producing anti-knock gasoline and low viscosity fuel oil which comprises commingling a stream of heavy hydrocarbon such as crude petroleum or reduced crude heated to 775-900° F. with a stream of hotter, fluid hydrocarbon, respectively accelerating and decelerating thereby the cracking rate of said heavy hydrocarbon and continuing the process in the manner aforesaid.
- 75 10. Process for producing anti-knock gasoline and low viscosity fuel oil which comprises commingling a stream of heavy hydrocarbon such as crude petroleum or reduced crude heated to 775-900° F. with a stream of hotter, fluid hydrocarbon, respectively accelerating and decelerating thereby the cracking rate of said heavy hydrocarbon and continuing the process in the manner aforesaid.

such resultant cracking rate for an interval short of detrimental carbon formation, separating generated vapors from residuum and withdrawing the latter as low viscosity fuel oil, dephlegmating the vapors to condense and separate recycle oil from gasoline vapors and separately condensing the latter as anti-knock gasoline, subjecting the recycle oil to cracking conditions of heat and pressure best suited to produce residual and vaporous fractions respectively adapted to liquid and vapor phase cracking, separating the residual fractions from the vaporous fractions and subjecting the latter to vapor phase cracking, commingling the products of such vapor phase treatment while still at a high cracking rate, as said hotter, fluid hydrocarbon, with a mixture of said residual fractions and said heavy hydrocarbon, and continuing the process in the manner aforesaid.

7. Process for producing anti-knock gasoline and low viscosity fuel oil which comprises commingling a stream of heavy hydrocarbon such as crude petroleum or reduced crude heated to a cracking temperature with a stream of hotter, fluid hydrocarbon, respectively accelerating and decelerating thereby the cracking rate of said heavy and said fluid hydrocarbons, reducing the viscosity and increasing the light fraction content of said heavy hydrocarbon by continuing such resultant cracking rate for an interval short of detrimental carbon formation, separating generated vapors from residuum and withdrawing the latter as low viscosity fuel oil, dephlegmating the vapors to condense and separate recycle oil from gasoline vapors and separately condensing the latter as anti-knock gasoline, subjecting the recycle oil in two portions to separate liquid phase cracking conditions of heat and pressure best suited to produce residual and vaporous fractions adapted to liquid and vapor phase cracking, separating the residual from the vaporous fractions and subjecting the latter to vapor phase cracking, admixing the unseparated products of liquid phase cracking of the other portion of the recycle oil with said residual fractions and uniting such admixture with the products of said vapor phase cracking as said hotter, fluid hydrocarbon, commingling the latter with said heavy hydrocarbon and continuing the process in the manner aforesaid.

8. Process for producing anti-knock gasoline and low viscosity fuel oil which comprises commingling a stream of heavy hydrocarbon such as crude petroleum or reduced crude heated to a cracking temperature with a stream of hotter, fluid hydrocarbon, respectively accelerating and decelerating thereby the cracking rate of said heavy and said fluid hydrocarbons, reducing the viscosity and increasing the light fraction content of said heavy hydrocarbon by continuing such resultant cracking rate short of detrimental carbon formation, separating generated vapors from residuum and withdrawing the latter as low viscosity fuel oil, dephlegmating the vapors to condense and separate recycle oil from gasoline vapors and separately condensing the latter as anti-knock gasoline, subjecting a portion of the recycle oil to liquid phase cracking conditions of heat and pressure best suited to produce residual and vaporous fractions respectively adapted to liquid and vapor phase cracking, separating the residual fractions from the vaporous fractions and subjecting the latter to vapor phase cracking, admixing the residual fractions with an

such mixture to liquid phase cracking conditions, uniting the products of such treatment with the products of said vapor phase cracking while still at a high cracking rate, as said hotter, fluid hydrocarbon, commingling the latter with said heavy hydrocarbon and continuing the process in the manner aforesaid. 5

9. Process for producing anti-knock gasoline and low viscosity fuel oil which comprises commingling a stream of heavy hydrocarbon such as crude petroleum or reduced crude heated to a cracking temperature with a stream of hotter, fluid hydrocarbon, respectively accelerating and decelerating thereby the cracking rate of said heavy and said fluid hydrocarbons, reducing the viscosity and increasing the light fraction content of said heavy hydrocarbon by continuing such resultant cracking rate short of detrimental carbon formation, separating generated vapors from residuum and withdrawing the latter as low viscosity fuel oil, dephlegmating the vapors to condense and separate recycle oil from gasoline vapors and separately condensing the latter as anti-knock gasoline, subjecting a portion of the recycle oil to liquid phase cracking conditions of heat and pressure best suited to produce residual and vaporous fractions respectively adapted to liquid and vapor phase cracking, separating the residual fractions from the vaporous fractions and subjecting the latter to vapor phase cracking, subjecting the residual fractions to liquid phase cracking conditions, uniting the products of such treatment with the products of said vapor phase cracking while still at a high cracking rate, as said hotter, fluid hydrocarbon, commingling the latter with said heavy hydrocarbon and continuing the process in the manner aforesaid.

10. Process for producing anti-knock gasoline and low viscosity fuel oil which comprises commingling a stream of heavy hydrocarbon such as crude petroleum or reduced crude heated to a cracking temperature with a stream of hotter, fluid hydrocarbon, respectively accelerating and decelerating thereby the cracking rate of said heavy and said fluid hydrocarbons, reducing the viscosity and increasing the light fraction content of said heavy hydrocarbon by continuing such resultant cracking rate for an interval short of carbon formation, admixing the products of such treatment with products of vapor phase cracking at their respective cracking temperatures, separating generated vapors from residuum and withdrawing the latter as low viscosity fuel oil, dephlegmating the vapors to condense and separate recycle oil from gasoline vapors and separately condensing the latter as anti-knock gasoline, subjecting the recycle oil in two portions to separate liquid phase cracking conditions of heat and pressure, separating one portion so treated into residual fractions and vaporous fractions and subjecting the latter to vapor phase cracking, commingling the unseparated products of liquid phase cracking of the other portion of the recycle oil, as said hotter, fluid hydrocarbon, with said heavy hydrocarbon, and continuing the process in the manner aforesaid. 40 45 50 55 60 65 70 75 80 85

11. Process for producing anti-knock gasoline and low viscosity fuel oil which comprises commingling a stream of heavy hydrocarbon such as crude petroleum or reduced crude heated to a cracking temperature with a stream of hotter, fluid hydrocarbon, respectively accelerating and decelerating thereby the cracking rate of said heavy and said fluid hydrocarbons, reducing the

- viscosity and increasing the light fraction content of said heavy hydrocarbon by continuing such resultant cracking rate for an interval short of carbon formation, admixing the products of such treatment with products of vapor phase cracking at their respective cracking temperatures, separating generated vapors from residuum and withdrawing the latter as low viscosity fuel oil, dephlegmating the vapors to condense and separate recycle oil from gasoline vapors and separately condensing the latter as anti-knock gasoline, subjecting the recycle oil in two portions to separate liquid phase cracking conditions of heat and pressure, separating one portion so treated into residual fractions and vaporous fractions and subjecting the latter to vapor phase cracking, commingling the unseparated products of liquid phase cracking of the other portion of the recycle oil, as said hotter, fluid hydrocarbon, in a relatively large ratio with said heavy hydrocarbon, and continuing the process in the manner aforesaid.
12. Process for producing anti-knock gasoline and low viscosity fuel oil which comprises commingling a stream of heavy hydrocarbon such as crude petroleum or reduced crude heated to a cracking temperature with a stream of hotter, fluid hydrocarbon, respectively accelerating and decelerating thereby the cracking rate of said heavy and said fluid hydrocarbons, reducing the viscosity and increasing the light fraction content of said heavy hydrocarbon by continuing such resultant cracking rate for an interval short of carbon formation, admixing the products of such treatment with products of vapor phase cracking at their respective cracking temperatures, separating generated vapors from residuum and withdrawing the latter as low viscosity fuel oil, dephlegmating the vapors to condense and separate recycle oil from gasoline vapors and separately condensing the latter as anti-knock gasoline, subjecting the recycle oil in two portions to separate liquid phase cracking conditions of heat and pressure, separating one portion so treated into residual fractions and vaporous fractions and subjecting the latter to vapor phase cracking, admixing the unseparated products of liquid phase cracking of the other portion of the recycle oil with the residual fractions, and the remaining portions of the products of vapor phase cracking, as said hotter, fluid hydrocarbon, commingling the latter with said heavy hydrocarbon and continuing the process in the manner aforesaid.
13. Process for producing anti-knock gasoline and low viscosity fuel oil which comprises commingling a stream of heavy hydrocarbon such as crude petroleum or reduced crude heated to a cracking temperature with a stream of hotter, fluid hydrocarbon, respectively accelerating and decelerating thereby the cracking rate of said heavy and said fluid hydrocarbons, reducing the viscosity and increasing the light fraction content of said heavy hydrocarbon by continuing such resultant cracking rate for an interval short of carbon formation, admixing the products of such treatment with products of vapor phase cracking at their respective cracking temperatures, separating generated vapors from residuum and withdrawing the latter as low viscosity fuel oil, dephlegmating the vapors to condense and separate recycle oil from gasoline vapors and separately condensing the latter as anti-knock gasoline, subjecting the recycle oil in two portions to separate liquid phase cracking conditions of heat and pressure, separating one portion so treated into residual fractions and vaporous fractions and subjecting the latter to vapor phase cracking, admixing the unseparated products of liquid phase cracking of the other portion of the recycle oil with the residual fractions, and the remaining portions of the products of vapor phase cracking, as said hotter, fluid hydrocarbon, commingling the latter with said heavy hydrocarbon and continuing the process in the manner aforesaid.

JOSEPH F. DONNELLY.
